UNITED STATES PATENT OFFICE.

JAMES ALEXANDER MACDONALD, OF BRANTFORD, ONTARIO, CANADA.

ELECTRIC WATER HEATER.

Application filed September 28, 1922. Serial No. 591,062.

To all whom it may concern:

Be it known that I, JAMES ALEXANDER MACDONALD, of the city of Brantford, county of Brant, Province of Ontario, Canada, 5 a subject of the King of Great Britain, have invented certain new and useful Improvements in Electric Water Heaters, of which the following is a specification.

This invention relates to heaters adapted 10 for heating water, and particularly to that type used in heating water in domestic hot water boilers. The object of the invention is to devise a construction which is interchangeable so that it may be used in 15 various ways, as for example, by being inserted directly in the interior of a hot water boiler, or by being mounted singly or in sets in a separate casing mounted alongside the boiler.

20 A further object is to devise a construction of heating element by the use of which greater efficiency will be obtained for the amount of current used.

Another object is to so arrange the heating element in its housing that it may be removed, and replaced with a similar element or with an element of larger or smaller capacity without in any way interfering with the water connections of the boiler or 25 casing, and to so arrange the connections that the connections outside the boiler or casing are insulated from the heat from the element, and also to so arrange the device that moisture from outside is prevented from 30 working in to the interior of the element housing.

The above mentioned and other objects are attained by means of the constructions hereinafter described and illustrated in the accompanying drawings in which 35

Fig. 1 is a longitudinal section of the improved heater as mounted on the interior of a domestic hot water boiler;

Fig. 2 a cross section through the heating element; and

Fig. 3 a cross section through the housing.

In the drawings like numerals of reference indicate corresponding parts in the different figures.

50 1 is part of the shell of a hot water boiler, which is provided with the usual threaded opening in its side. 2 is the housing for the heater, which housing is preferably formed of brace tubing and has one closed

end. To the open end of the housing 2 is 55 secured the sleeve 3, having a threaded portion thereon adapted to fit the threaded opening in the boiler 1.

On the end of this sleeve 3 is cast a band 4 preferably of aluminum, the sleeve being 60 provided with grooves or recesses 5 in which the metal of the band is adapted to run to anchor the band on the sleeve. The wrench used for installing the device is applied to this band 4, and there is therefore no danger 65 of distorting or damaging the housing 2 or sleeve 3 by the wrench.

It will be noted on reference to the drawings that the exterior surface of the housing is provided with a series of corrugations 70 6, which corrugations may be formed as a spiral thread. These corrugations not only increase the heating area of the housing, but it is found in practice that a housing provided with these corrugations is not 75 nearly so liable to twist or warp, as a housing without these corrugations.

The heating element comprises a core or base 7, preferably of soapstone as this material possesses two important features not 80 found in porcelain which has heretofore mainly been used for this purpose. One of these features is that the soapstone more rapidly absorbs and conducts heat from the resistance and the other feature is that it 85 retains the heat for a considerable time once it has become saturated.

In this core 7 are formed, by machining, a plurality of longitudinal slits 8, and in these slits is wound the resistance winding 90 9. This resistance winding is formed as a ribbon and is set on edge in the slits. At least sufficient high temperature heat conducting dielectric cement is then placed in the slits to properly retain the resistance 95 winding in place. When the setting of the cement has reached a certain point, the current is turned on the resistance winding and as it expands it forces back the cement sufficiently to always give the winding room 100 for expansion. The winding is then at perfect liberty to expand in the slits and there is therefore no danger of the winding suffering from any undue expansion strains.

To hold the resistance winding in place 105 while the cement is being filled in the slits and setting, annular grooves 10 are formed in the core and in each of these grooves a

thread is wound over the resistance winding.

With the core and resistance constructed as described, it is found that the heat from the resistance winding is absorbed by the core as shown as generated so that the resistance winding, when in the housing and the housing immersed in water, always burns at a black temperature, which is in marked contrast to previous constructions in which the resistance winding burns at all the way from a dull red to a white heat. The advantages derived from this lower working temperature of the resistance winding and the higher temperature imparted to the core is that the heater operates with greater speed and efficiency and there is not the danger of the winding burning out.

At one end of the core is formed, preferably integral therewith, the spacer 11 to hold the core spaced from the closed end of the housing 2. At the other end of the core preferably integral therewith is formed the block 12 and in each side of this block is formed a groove 13. The ends of the resistance winding 9 are led one into each of these grooves.

Heretofore it has usually been the practice to provide suitable bolts and nuts for securing the ends of the resistance winding to the leads. Due to temperature stresses and other causes these bolts and nuts in time become loose, thereby impairing the contact electrically as well as mechanically. To overcome this the lead wires 14 are led one into each groove 13 where they are connected with the ends of the resistance winding, the joints being fused into practically a solid piece of metal. The joints are then embedded by filling the grooves with cement.

To prevent moisture working into the interior of the housing 2, the space around the wires 14 within the sleeve 3 is packed tightly with asbestos fibre 16. The outside air passes very slowly through this packing, and while doing so is preheated, and when it strikes the hot solid end of the soapstone core it is further preheated, and there is therefore no danger of moist air passing through into the interior of the housing to condense and drop on to the resistance winding, and there is thus also avoided the usual noise caused by condensation within the housing.

To prevent the heat from the device being conducted to the connections outside the tanks, washers 17 of asbestos or like material are placed between the ends of the sleeve 3 and band 4 and the end of the connector 18. These washers are provided with holes only of sufficient size for the passage of the wires 14. The connector 18 is secured in position by screws 19 passing through the washers 17 into the end of the band 4.

22 is a conduit the end of which is adapt-

ed to be secured in the connector 18. This conduit may be turned to extend in any direction, and is held in place as adjusted by means of set screws 20.

The wires 14 are led into the interior of the conduit, where they are connected in any suitable manner with the service wires 21.

From the construction described it will be seen that a compact and effective arrangement has been devised; that there is no necessity of removing the housing once it is in position; that the heating element is easily removed and replaced if necessary; that there is little danger of moist air working into the interior of the housing; that the outside connections are well heat insulated from the heating element; and finally that the method of mounting the winding on the core is one which will result in the winding having a very long life.

As stated in the preamble of the specification, it will be understood that the heater might be mounted in a separate casing from the water tank or that two or more heaters may be mounted in a single casing, and in the latter case the heaters will be so connected that one or more may be used as desired to give a number of different heats.

What I claim as my invention is:—

1. In an electric heater, the combination of a substantially solid cylindrical core of refractory non-conducting material having a plurality of narrow slits formed longitudinally thereof; and a resistance element of lesser depth than and mounted in said slits, said resistance being held in the bottom of the slits by dielectric cement.

2. In an electric heater, the combination of a core of refractory non-conducting material having a plurality of slits formed longitudinally thereof; and a resistance element mounted in said slits, said slits being closed by dielectric cement, said element being free to expand in said slits.

3. In an electric heater, the combination of a substantially solid cylindrical core of refractory non-conducting material having a plurality of narrow slits formed longitudinally thereof; and a ribbon resistance element of lesser width than the depth of the slits and set on edge in said slits, said resistance being held in the bottom of the slits by dielectric cement.

4. In an electric heater, the combination of a core of refractory non-conducting material having a plurality of slits formed longitudinally thereof; and a ribbon resistance element set on edge in said slits, said slits being closed by dielectric cement, said element being free to expand.

5. The process of forming an electric heater having a core of refractory non-conducting material having slits formed longitudinally thereof; which consists in wind-

- ing a resistance element in said slits; placing dielectric cement in said slits to hold the element in position; and supplying current to the element before the setting of the cement is complete. 5
6. The process of forming an electric heater having a core of refractory non-conducting material which consists in machining slits in said core longitudinally thereof; 10 winding a resistance element in said slits; placing dielectric cement in said slits to hold the element in position; and supplying current to the element before the setting of the cement is complete. 15
7. The process of forming an electric heater having a core of refractory non-conducting material having slits formed longitudinally thereof which consists in winding a ribbon resistance element on the edge in said 20 slits; placing dielectric cement in said slits to hold the element in position; and supplying current to the element before the setting of the cement is complete. 25
8. In an electric heater, the combination 30 of a housing having one closed end; a solid removable core of refractory non-conducting material in said housing, a space being left at the open end of the housing; a resistance element on said core; lead wires connected with the resistance element; means for closing the open end of the housing, said space being packed with a loose fibrous non-conducting material. 35
9. In an electric heater, the combination 40 of a housing; a core of refractory non-conducting material in said housing; a resistance element on said core; a fitting into which lead wires may be led; means connecting the fitting to the housing; said fitting being heat insulated from the housing. 45
10. In an electric heater, the combination 50 of a housing for a heating element; a fitting into which lead wires may be led; means connecting the fitting to the housing; and an asbestos washer between the housing and the fitting. 55
11. In an electric heater, the combination 60 of a housing; a core of refractory non-conducting material in said housing; and a resistance element on said core, said housing being provided with a series of corrugations on its outer surface. 65
12. In an electric heater, the combination 70 of a housing; a core of refractory non-conducting material in said housing; and a resistance element on said core, said housing being provided with a series of circumferential corrugations. 75
13. In an electric heater, the combination 80 of a housing for a heating element, said housing having a threaded portion on its outer surface slightly spaced from one end and grooves in the outer surface of the end; and a band cast on said end and anchored 85 in said grooves. 90
14. In an electric heater, the combination 95 of a core of refractory non-conducting material; a resistance element on said core; and lead wires connected with the ends of the resistance element, the lead wires and the ends of the element being integrally united. 100
15. In an electric heater, the combination 105 of a housing and a core of refractory non-conducting material; a resistance element on said core; and lead wires extending into said housing and connected with the ends of the resistance element, the lead wires and the ends of the element being integrally united. 110
16. In an electric heater, the combination 115 of a core of refractory non-conducting material; a resistance element on said core, said core being provided with grooves adjacent one end into which the ends of the resistance element are led; lead wires extending into said grooves and connected with the ends of the resistance element, the wires and elements being integrally united, 120 said grooves being packed to enclose the joints between the wires and elements. 125
17. In an electric heater, the combination 130 of a housing for a heating element, said housing being provided with a series of corrugations on its outer surface; a conduit for lead wires; means connecting the conduit to the housing; and means for checking the passage of heat from the housing to the conduit. 135
18. In an electric heater, the combination 140 of a housing and a core of refractory non-conducting material; a heating element; and lead wires extending into said housing and connected with the ends of the resistance element, the lead wires and the ends of the element being integrally united, said housing being provided with a series of corrugations on its outer surface. 145
19. In an electric heater, the combination 150 of a core of refractory non-conducting material having a plurality of slits formed longitudinally thereof; a ribbon resistance element set on edge in said slits, said resistance being held in position by dielectric cement; and lead wires connected with the ends of the resistance element, the lead wires and the ends of the element being integrally united. 155
20. In an electric heater, the combination 160 of a core of refractory non-conducting material having a plurality of slits formed longitudinally thereof; and a ribbon resistance element set on edge in said slits, said resistance being held in place with dielectric cement, said core also being provided with grooves adjacent one end into which the ends of the resistance element are led; lead wires extending into said grooves and connected with the ends of the resistance element, the wires and elements being in- 165

tegrally united, said grooves being packed to enclose the joints between the wires and element.

21. In an electric heater, the combination of a housing having one closed end; a removable core of refractory non-conducting material in said housing, a space being left at the open end of the housing; a resistance element on said core; lead wires connected with the resistance element; means for closing the open end of the housing, said space being packed to check the admission of moisture to the interior of the housing, said housing being provided with a series of corrugations on its outer surface.

22. In an electric heater, the combination of a housing, for a heating element, said housing having a threaded portion on its outer surface slightly spaced from one end and grooves in the outer surface of the end; and a band cast on said end and anchored in said grooves, the remainder of the outer surface of the housing being provided with a series of corrugations.

23. In an electric heater, the combination of a housing having one closed end; a removable core of refractory non-conducting material in said housing, a space being left at the open end of the housing; a resistance element on said core; lead wires connected with the resistance element; means for closing the open end of the housing, said space being packed to check the admission of

moisture to the interior of the housing; and a conduit secured to said housing, said first mentioned means being adapted to prevent heat passing from the housing to the conduit.

24. In an electric heater, the combination of a housing having one closed end; a removable core of refractory non-conducting material in said housing, a space being left at the open end of the housing; a resistance element on said core; lead wires integrally united with the resistance element; means for closing the open end of the housing, said space being packed to check the admission of moisture to the interior of the housing.

25. In an electric heater, the combination of a housing, for a heating element, said housing having a threaded portion on its outer surface adjacent one end, said end having an irregular outer surface; and a band cast on said end having the irregular outer surface.

26. In an electric heater, the combination of a housing for a heating element; a fitting into which lead wires may be led; means connecting the fitting to the housing, said fitting being adapted to be rotarily adjustable relative to the housing, said fitting being heat insulated from the housing.

Signed at Brantford, Ont., this 18th day of September, 1922.

JAMES ALEXANDER MacDONALD
